UNITED STATES PATENT OFFICE.

HILLIARD M. JONES, OF STOCKTON, CALIFORNIA.

COUPLING-LINK.

SPECIFICATION forming part of Letters Patent No. 271,713, dated February 6, 1883.

Application filed June 17, 1882. (No model.)

To all whom it may concern:

Be it known that I, HILLIARD M. JONES, of Stockton, county of San Joaquin, State of California, have invented an Improved Coupling-Link; and I do hereby declare the following to be a full, clear, and exact description thereof.

My invention relates to a new and useful coupling-link; and it consists in a metal ring or link with separated ends, in one of which a peculiar latch is pivoted or hinged, the other end of which is adapted to fit into and be secured in a socket in the other end of the link, all of which will hereinafter fully appear.

The object of my invention is to provide a convenient, effective, and economical device for coupling any desired number of chains.

My special object in this invention is to adapt it for use in harness in coupling side and fifth chains of the forward team to the fifth chain of the team behind.

Referring to the accompanying drawings, Figure 1 is a perspective. Fig. 2 is a perspective, showing side, rear, and forward fifth-chains attached. Fig. 3 is an elevation. Fig. 4 is an elevation.

Let A represent a metal ring or link of suitable weight and strength, and of any desired shape—elliptical, circular, or otherwise. This link is not a perfect one, its ends being separated and at some distance apart, as shown. In one of its ends an aperture, a, is made, in which is pivoted the latch B. This consists of a strong metal bar, the end of which is curved around through aperture a, and embraces the end of the link. The body of this latch is curved, as shown, and is provided with a hook or point, b, the outer face of which has a shoulder, c.

In the other end of the link a socket or aperture, a', is made, the rear wall of which is sloped or beveled from the back upon its inner side forward to its outer side. Its forward wall is sloped from the outer side backward to the inner side.

When the latch B is turned to close the link, its pointed or hooked head slips through the beveled socket and engages with the forward beveled wall, against which it is braced to re-

sist the outward strain, and also the side strain, as I shall show. To lock it in place, I have a 50 spring, D, secured at its rear end to the outer side of the link. Its forward end impinges behind the shoulder c of the point b, and prevents it from being forced back and out of the socket a'. 55

In using this link, the spring is raised slightly to free the point b, and the latch B is turned back in the link against the opposite side, thus opening the link. The position of the locking-spring may be changed without affecting the invention. The ordinary end links of the chains to be coupled are then slipped upon the link A through the opening, and the latch is closed and locked, thus securing them.

In order to show its particular adaptation I 60 refer to Fig. 2.

It is customary, when a heavy load has to be drawn, to couple several teams together. The rear team is harnessed to the wagon in the usual manner and the next team is coupled to 70 the first by means of side chains and a fifth-chain, the rear ends of which meet in an ordinary link or ring, which is provided with a hook. This hook engages with the link at the forward end of the fifth-chain behind. 75 The difficulty with this is that special preparation of these chains is necessary to weld them within a common link, which must be provided with a hook. Again, upon hilly roads the hook is liable to become unclamped and cause 80 trouble.

E represents the side chains, E' the rear fifth-chain, and E² the forward fifth-chain.

I take first the rear fifth-chain, E', and slip its ordinary end link upon the coupling-link A. 85 Then the side chains are placed in the coupling-link on each side, and finally the forward fifth-chain, E², is placed within it, all having no other formation than the ordinary links. Then I close the latch B. All the chains are 90 in position upon the coupling-link. The side strain upon the link is resisted by the latch, and the end strain, which has a tendency to elongate the link, is also resisted by said latch, which acts as a brace for the link and prevents 95 it from being drawn out.

Having thus described my invention, what I claim as new, and desire to secure by Letters Patent, is—

The coupling-link A, having separated ends, 5 in one of which a socket, *a*, is formed, and in the other the beveled socket or aperture *a'*, in combination with the latch B, hinged or pivoted in the socket *a*, and having a point or hook, *b*, with a shoulder, *c*, for fitting in the beveled

aperture *a'*, and the locking-spring D, engaging with the shoulder *c*, substantially as herein described.

In witness whereof I hereunto set my hand.

HILLIARD M. JONES.
